UNITED STATES PATENT OFFICE

108,610

DESIGN FOR A COMBINED CIGARETTE AND CANDLE HOLDER

Robert L. R. Bartholomew, Chester Springs, Pa.

Application December 21, 1937, Serial No. 73,782

Term of patent 3½ years

To all whom it may concern:

Be it known that I, Robert L. R. Bartholomew, a citizen of the United States, residing in Chester Springs, in the county of Chester, State of Pennsylvania, have invented a new, original, and ornamental Design for a Combined Cigarette and Candle Holder, of which the following is a specification, reference being had to the accompanying drawing, forming part thereof.

Fig. 1 is a side elevation in normal position of a combined cigarette and candle holder, showing my new design.

Fig. 2 is a front elevation of same.

Fig. 3 is a side elevation of the same in the serving position.

I claim:—

The ornamental design for a combined cigarette and candle holder, as shown and described.
